UNITED STATES PATENT OFFICE.

GEORGE B. MARKOE, OF BRIGHTON, MASSACHUSETTS.

OIL BURNER.

Application filed September 11, 1924. Serial No. 737,079.

This invention relates to improvements in oil burners. More particularly it provides a burner for kerosene, furnace oil or other suitable oil, which is adaptable for domestic as well as industrial use, as for example in a house heating system. It is an important feature of the invention to apply the vapor of water in connection with the vapor of oil so as to get an efficient flame giving great heat and free from smoke and from solid deposits in the apparatus. It may be applied to burners heretofore proposed for such purposes using oil alone, in which case the apparatus of the invention, by its introduction of steam, converts the lazy flame of the oil alone into a rather fierce flame, bluish and reddish in color.

In the apparatus of the invention vaporizer chambers are employed, which may be simple closed sections of two inch pipe, separate chambers being provided for oil and for water, with discharge connections by which the oil and the water vapors unite, and are projected downward through a coil of small pipe holding oil vapor, and superheating the latter just before its discharge and combustion. The oil and the water are introduced to their respective vaporizers, each by a small pipe which lets the liquid fall drop by drop upon a hot interior surface of the vaporizer, generating pressure which acting through the discharge pipe forces the oil and vapor into their mixture and into the flame.

The details of apparatus illustrative of the invention, and further principles of its construction and operation, will appear in the description of one embodiment thereof which follows. It will be understood however that variations may be made in sundry respects without departing from the scope of the invention. It is intended that the patent shall cover by suitable expression in the appended claims whatever features of patentable novelty exist in the invention disclosed.

In the accompanying drawings;

Figure 1 is an elevation, partly diagrammatic, showing an embodiment of the invention resting above a grate such as may be found in an ordinary furnace that was designed for combustion of coal.

Figure 2 is a plan of the same.

Figure 3 is an elevation in section through a fragment of a vaporizing chamber, being

on the line 3-3 of Figure 2, on a larger scale.

Figure 4 is an elevation in section through a portion of the delivery and combustion part of the apparatus, being on the line 4-4 of Figure 2.

Figure 5 is an elevation in section through a part of the air supply and the combustion arrangements, on the line 5-5 of Figure 2.

Referring to the drawings, 10 indicates the wall of a furnace having a grate 11 which in the present instance is used only as a support for masonry 12 that holds a horizontal partition or internal sill 13 on which the base portion 14 of the apparatus is set. This base portion is an upward passage for air, as seen in Fig. 5. Air rising through it passes through tubes 15, of which there are four in the present case each arranged to conduct its air radially inward to the center and to discharge it downward through the opening 16, to feed the center of a flame of oil which has risen centrally to the same region through pipe 20. This oil from pipe 20 wells up through a small passage 22 in a spreader head 24 and flows outward over its gently descending surface, burning as it goes, with the air from 16 above it supporting its combustion and with the products of combustion escaping from all sides through the spaces 25 which intervene between the said air supply tubes 15. The burner thus described is of a type already known to which the present invention may advantageously be applied to improve the flame; or which may be associated with apparatus of the invention for starting the latter into action as a burner by providing its necessary preliminary heating, after which the feed of oil to the above described burner may be shut off.

In the embodiment illustrated the apparatus above described is surrounded by the vaporizer chambers 31, 32 and 33 which may conveniently be made by bending 100 lengths of 2 inch pipe or other suitable size, each into an arc of a circle around the said starting burner. As represented, these are set one vertically over another, the middle one occupying about three-fourths of a circumference, the under one more and the upper one less. One end of each has an inlet for oil fuel, or water, of which the construction shown in Fig. 3 is typical, the inlet pipe 36 projecting inward axially

through an end closure 37, and there being a suitable stuffing box 38. The other end of each chamber is closed by a cap 37' except for a discharge pipe 39 which rises from the side of the cap 37'. Water entering through the pipe 36 at a slow rate, controllable by a needle valve (not shown) on its supply line 40, drops occasionally as seen at 41 from this inside end of the supply pipe 36. The drops fall upon the hot wall of the vaporizer 33, and the resulting steam passes around through the chamber, becoming somewhat superheated and flows out through the small pipe 39 and is conducted thereby into 15 the top middle of the burner first described where it discharges downward over the opening 16 and mixes its steam with the air entering through 15 so that the two together are present for the combustion of the oil which 20 is simultaneously welling up through the pipe 20 and flowing over the burner and spreader 24. If it be desired, a single vaporizer for water such as this chamber 33 may thus be combined with a burner of 25 the previously known type above described with notable benefit in quality of flame, completeness of combustion, freedom from smoke and deposits, and with greater output 30 of heat due to the pressure and other qualities which the steam jet introduces. In this case for starting, the vaporizer 33 is first heated by the oil flame at 24 burning in air; and after steam begins to be generated the combustion is continued at this 35 burner alone with aid of the steam. Or, before steam is generated, compressed air forced through the vaporizer becomes heated therein and by aiding the combustion hastens the time when steam can be helpful. 40 Means for doing this is shown diagrammatically in Figure 1 where the water pipe 60 is represented as being supplied either from a source of water controlled by a valve 60' or supplied by a source of air consisting of 45 a tank 60^a wherein air may be compressed by a pump 60^b and from which air flows to the pipe 60 through a control valve 60''. However, the vaporizers 31 and 32 may 50 be employed to make a combustible mixture through another burner. In this case the lowest chamber 31 is a vaporizer for the oil fuel which enters as a liquid through a small pipe 50 corresponding to the supply pipe 40 and passes on as a vapor through the 55 vaporizer and out through the discharge pipe 49 which is a small pipe arranged as a coil 51, having several convolutions. From the last of these the oil vapor is conducted through pipe 52, upward, laterally and 60 downward, by as short a course as is convenient, to a T 53 whence it issues through the discharge or burner tube 55 by which its flame is projected down through the 65 midst of the said coil 51. This flame may strike on fire brick or other spreader if de-

sired. In the present drawings the representation of such is omitted but the flame is in line with the plate 26 which constitutes a spreader for the flame issuing from the first described burner through the opening 25. 70 The flame shooting down through the coil 51 super-heats the vapor which is passing through that coil.

From the vaporizer chamber 32, steam which has entered as water through the supply pipe 60, corresponding to 40, issues through the discharge pipe 59 and enters the same T 53 where it adds itself and its pressure to the oil vapor, going out with the latter through the burner 55 and the flame 80 therefrom.

When the vaporizers 32 and 33 have gotten sufficiently heated to be working, the flame in the burner 14 may be shut off or may be continued as may be desired. If 85 it be desired to dispense entirely with the first mentioned burner 14, this may be done through the means of a priming arrangement indicated at 69 which leads into the T 53 and into which oil may be introduced through the supply pipe 70. This oil runs by gravity to the bottom of the burner 55 and there burns in air alone, gradually heating the coil 51 and vaporizers 31 and 32. When they are sufficiently heated 90 they come into action and the infeed of priming oil through 69 may be stopped. Any suitable valves (not shown) may be provided for controlling the several supplies. 100

The starting operation of the burner may be expedited by passing compressed air through either or both of the steam generators, in place of introducing water. Through suitable connections air may be let 105 into the water inlet 40 or 60, or both, from a small tank or compressor of air, for a few minutes. This hastens the flame, and heats the walls of the steam generator so that the air passing therethrough soon becomes 110 heated air; and this further expedites the heating of the steam generator, instead of delaying it as the introduction of cold water does when the flame is new and small. When well heated the air connection may be 115 shifted to a water supply connection. Such air may be conveniently held ready in a small tank, say of 30 gallons capacity, at a pressure of 30-50 pounds, from which a 120 five minutes' flow of a small stream will serve the above purpose without greatly reducing the supply.

I claim as my invention:

1. An oil burner including an oil vapor generating chamber; means for supplying oil thereto; a discharge tube for the vapor there generated, leading thence upward and thence directed downward toward the said generator, for operating the same by the flame of the burner; and a preliminary oil 125 130

- supply tube, leading into the said downward discharge tube, whereby liquid oil may be discharged toward the generator for preliminary heating thereof.
- 5 2. An oil burner comprising generating and superheating chambers for vapor, the generator being a pipe of large diameter, curved horizontally around the combustion space and the superheater being pipe of 10 small diameter coiled in a helix of small diameter on an upright axis, with a discharge nozzle connected to its end and directed downward through the superheating coil and within the curve of the generating 15 chamber.
3. An oil burner comprising separate generator chambers from one of which there is a discharge passage of small diameter arranged in a helical course, and from the 20 other of which there is a discharge passage joining the first mentioned discharge passage beyond the helix; the outlet from the joint discharge passage being directed backward placing the flame within said helix 25 and toward the generator.
4. An oil burner having an oil vapor generating chamber comprising a curved tube of large diameter extending through the greater part but not the whole of a circle; 30 an adjacent similar tube, parallel thereto and substantially on the same axis, adapted for generating steam; connections of small diameter piping to each for inlet of liquid at its one end and for outlet of vapor at its 35 other end, the inlet and outlet small piping passages being thus assembled on the one side where the circle is not continued; the two outlet pipes being joined; and their joint passage arranged to discharge the two 40 vapors mixed therein through a small opening into unconfined air in the space surrounded by the curved chambers.
5. An oil burner having a vapor generating chamber comprising a curved tube of 45 large diameter extending through the greater part but not the whole of a circle; a superheating outlet passage therefrom of small pipe arranged in a small coil located in the side where the circle is not continued, 50 and a discharge from the superheating coil directed downward through it in position to heat it and the generating tube.
6. An oil burner having a nozzle pointed downward for the discharge of oil to the flame and means for supplying oil thereto 55 for initial flame; combined with a vaporizing chamber for oil and means for supplying oil to it at a limited rate; a second chamber and means for supplying air to it under pressure; the said two chambers being positioned to be heated by the said initial flame and having discharge passages leading their contents to the flame; and means for supplying water to the second said chamber, for its vaporization to steam when 60 said second chamber shall have become heated.
7. Oil burning apparatus comprising the combination of a burner with means to supply to it liquid oil and compressed air for 65 combustion; a chamber through which the said air passes en route to the burner, so located as to be heated by the flame of the burner; and means to supply water to the 70 said heated chamber for the making of steam therein for the flame; the said means for supplying liquid oil having a part arranged to deliver oil by gravity to the burner, and a part arranged to deliver oil to the burner by vaporization; said last 75 mentioned part being arranged to be heated by the flame of the gravity-delivered oil, thereby to initiate the said vaporization, and to be heated by the flame of the vaporization-delivered oil, thereby to continue the vaporization.
8. Oil burning apparatus comprising the combination of a burner with means to supply oil to two portions of the apparatus, at 80 one of which portions is a discharge opening for combustion of the oil supplied thereto, the whole being arranged for the flame thereof to heat the other said portion to which oil is supplied, and thus to vaporize and feed to the said flame by its own vapor pressure the oil so supplied to said other portion; a conduit for compressed air to the same said flame, having a part heated by 85 said flame; and means to supply water instead of air to said conduit, whereby steam 90 is supplied to the flame.
- Signed at Boston, Massachusetts, this ninth day of September 1924.
